[57] CLAIM

The ornamental design for a food product, as shown and described.

DESCRIPTION

FIG. 1 is a top plan view of a food product showing my new design, the undisclosed bottom being a mirror image;

FIG. 2 is a right end elevational view thereof;

FIG. 3 is a left end elevational view thereof;

FIG. 4 is a front elevational view thereof, the undisclosed rear being a mirror image;

FIG. 5 is a top plan view of a second embodiment of FIG. 1, the undisclosed bottom being a mirror image; and,

FIG. 6 is a right end elevational view of the second embodiment of FIG. 5, the undisclosed left end being a mirror image.

It is understood that the undisclosed front and rear elevational views of the second embodiments (FIGS. 5 and 6) are the same as FIG. 4.
